UNITED STATES PATENT OFFICE.

JOHN A. BOEHRINGER, OF SPRINGFIELD, NEW YORK, ASSIGNOR TO STAR CHANDELIER CO., INC., OF NEW YORK, N. Y., A CORPORATION OF NEW YORK.

DESIGN FOR AN ARM FOR AN ELECTRIC WALL-BRACKET PLATE OR SIMILAR ARTICLE.

Application filed November 17, 1927. Serial No. 24,179. Term of patent 3½ years.

To all whom it may concern:

Be it known that I, JOHN A. BOEHRINGER, a citizen of the United States, residing at 145-85 Aberdeen Street, Springfield, Long Island, in the county of Queens and State of New York, have invented a new, original, and ornamental Design for an Arm for an Electric Wall-Bracket Plate or Similar Article, of which the following is a specification, reference being had to the accompanying drawing, forming part thereof.

The figure is a perspective view of an arm for an electric wall bracket plate, or similar article, showing my new design.

I claim:

The ornamental design for an arm for an electric wall bracket plate or similar article, as shown.

JOHN A. BOEHRINGER.
